ROTARY FAN

Filed Aug. 3, 1928

William P. Aron,
INVENTOR.

BY Ernest G. Hood

ATTORNEY.

UNITED STATES PATENT OFFICE

WILLIAM P. ARON, OF DALLAS, TEXAS, ASSIGNOR TO OSCAR W. LUDWICK, OF DALLAS, TEXAS

ROTARY FAN

Application filed August 3, 1928. Serial No. 297,169.

This invention relates to electrical apparatus and equipment and it refers more particularly to electric fans and ventilating units, the principal object of the invention residing in the provision of a propeller having the wind impelling characteristics of an air plane propeller and provided with a motor having direct connection with the propeller, and by reason of which positive and varied speed drive way be assured.

A further object of the invention resides in the provision of relatively rotatable contact plates, one of which is held stationary with respect to the fan suspension means and the other stationary with respect to the fan motor, and through the medium of which the entire structure is capable of rotation with respect to its mounting.

A particularly important object of the invention resides in the provision of wind deflector embracing the motor of the fan and so arranged that angular displacement of the motor with respect to its point of suspension will cause the same to deflect air currents created by said propeller and thus bring about rotation of the motor in either direction, depending upon the angle of adjustment. Moreover, by reason of the relative size and speed of the propeller, combined with the relationship therewith of the deflector, a swirling suction is created beneath the structure, drawing the air violently upward and thus bringing about maximum circulation.

Still another object of the invention resides in the provision of a means to arrest rotation of the fan at any position desired without interfering with the action of the propeller.

With the foregoing objects as paramount, the invention especially pertains to its salient features of construction and operation of parts, to become manifest as the description proceeds, taken in connection with the accompanying drawings wherein:

Figure 1 represents a perspective view of a fan constructed to embody the principle of the present invention.

Figure 2 is a side elevational view.

Figure 3 is a detail view in diametrical

section, of the mechanism designed to impart rotation to the fan, and

Figure 4 is a plan view on lines 4—4 of Figure 2.

Continuing now more in detail with the drawings, 1 designates an electric motor, upon the armature shaft 2 of which is mounted the propeller 3. Particular note will be taken of this propeller, its relative size and the angle of pitch of the blades, through which maximum wind excitation is established, and due to the direct drive from the motor, lost motion and friction is reduced to the very minimum. It is desirable that the motor 1 be capable of operating at varied speeds, controllable through the rheostat switch 4 depending to an accessible point from the floor.

It may be stated at this point that while the drawings show the motor 1 as being supported on a horizontal plane with respect to the suspension means, in order to obtain maximum results in rotation of the motor, it is intended that the same shall be operative on an inclined plane, that is to say, when the propeller 3 is directed slightly downward, the direction of rotation will be anti-clockwise, and when inclined upward, direction of rotation will be opposite. The reasons for this will be explained in detail during the course of description.

The suspending and rotating means are comprised primarily of a hollow conduit 5, secured by joint 6 to center stem 7. An element 8, which will be hereinafter termed armature plate, is held stationary with stem 7 by set screw 9.

The stem 7, as apparent in Figure 3, has an enlargement 10, above which is mounted a roller bearing 11, to hold which, a cup member 12 is mounted on the stem and encases the bearing. As apparent also in Figure 3, this member 12 is exteriorly threaded on its lower portion to receive an interiorly threaded retainer ring 13.

A supporting bracket 14, having integral arms 15, the ends of which are bent to embrace the motor 1 as apparent in Figures 1 and 2, is provided and apertured to enable the cup member 12 to pass therethrough, thus

the said bracket member is securely held, as is the other elements of the assembly, by the retainer ring 13, when operatively applied. Obviously however, the stem 7 is capable of non-frictional rotation with respect to the cup member 12, retainer ring 13, and other mentioned elements, that is to say, rotative relationship between the stem and the other described elements is provided.

10 The arms 15 of bracket 14 are pivotally held to the sides of motor 1 by nuts 16 threaded over protruding bolts affixed to the motor. Thus, the motor is capable of rocking movement with respect to its axis on the described 15 suspension means, to bring about opposite rotation and for other purposes.

10 Encircling the cup member 12 is a member 17 which shall be hereinafter referred to as the contact plate, and which is insulated from the cup member 12 by a ring 18 composed of non-conductive material. This plate 17 has embedded in its operative surface annular contact rings 19, as also apparent in Figure 3, and it is the inner contact ring, instead of 25 the plate 17 that is required to be insulated from cup member 12, since the plate 17 itself is composed of non-conductive material. It is also seen in Figure 3 that an intermediate annular ridge 20, is formed between the contact rings 19 from the plate 17 to insulate.

15 Wires 21, separately connected to the contact rings 19, convey current therefrom to the motor 1, as apparent in Figures 2 and 3. Therefore, to complete the circuit through 20 these rings 19, contact posts 22 are provided and detachably held secure to the armature plate 8 by nuts 23. The contact posts 22, being recessed at one end, as apparent in Figure 3, are capable of receiving carbon brushes 24, 25 held normally against the contact rings 19 by springs 25 encased within hollow sleeve member 26, threaded into the recess in the end of the contact post 22, and so flanged at its lowermost end as to constrain the brush 24 against dislodgement. It will be observed that one of the brushes 24 has slidable engagement with the inner contact ring 19 while the other contacts in a similar manner with the outer ring 19. Thus a constant and uninterrupted current is established to the motor 1 through the relatively rotatable plates 8 and 17 from the source through wires 27, entering through the hollow conduit 7, one of which is connected to each of the brushes 24, in the 30 manner shown in Figure 3.

19 The directions of air currents incited by the propeller 3 are directed rearwardly, that is, in the direction of the motor 1, due to the angle of pitch of the blades. The deflector, 35 comprised of fins 28 is attached to the motor by brackets 29 at either end of the latter and is further held by bracket at 30 against which is urged the nut 16 employed for securing the arms of the suspension means. To cause rotation of the entire structure, the fins 28 are

warped to receive the air currents directed by the fan, the action of the blades of the propeller driving the air forcibly thereagainst, and the angle to which the fins are warped determines the direction in which the structure will rotate.

70 It is understood that if one of the fins 28 of the fan is warped to a greater angle than the companion fin, the surface exposed to the air currents excited by the propeller 3, will be greater and consequently the entire structure will be thereby revolved. In order to effect rotation of the structure in an opposite direction, it is necessary only to manually 75 change the angle of warp in the fins, being careful that one fin receives only a minimum of the air currents while the other receives the maximum. It is necessary that the fins be arranged at different angles before any 80 rotary movement of the structure is possible.

85 The fins 28 comprising the deflector must be on an inclined plane relative to the motor before the fan will effect rotation on its suspension.

90 It has been made clear that the lower plate 17 is rotative with respect to the upper plate 8, the latter being stationary with the supporting conduit 5. The cup shaped member 12, being stationary with respect to the lower plate 17 therefore revolves around the stem 7 95 through which passes the wires 27. The stem 7 has been mentioned as having an enlargement 10 on its lower end and as shown in Figure 3. To this enlargement is secured by screws 31 a cylindrical member 32, the periphery of which is smooth, and is slightly smaller in circumference than the smooth inner periphery of the cup shaped member 12 in which it is received. This affords a braking surface against which the threaded element 33 is urged, as apparent in Figure 3.

100 To more fully explain this brake, the retainer ring 13 applied to secure the structure to the support, has integral therewith an interiorly threaded boss 34, extending laterally 105 from its side, into which is threaded the element 33, which as apparent in Figure 3 is slotted longitudinally to insure proper tension. When this element or brake screw 33 is rotated in a clock-wise direction, it is urged 110 against the cylinder 32, binding the same against further rotation, consequently arresting the rotative action of the fan without affecting the movement of the propeller 3.

115 In order to accomplish the foregoing from a convenient point on the floor, lateral arms 35 are applied to the outer end of the brake screw 33, as shown especially in Figure 4, depending from the ends of which are cords 36. A pull upon one of the cords will bring the screw into operative engagement with the cylinder 32, while a pull upon the other will relieve the binding action thus created, enabling the fan to resume normal rotation.

120 Briefly setting forth the operation of the 130

fan; the current passes through the wires 27, through brushes 24 into contact rings 19, thence through wires 21 to motor 1 to operate the same. Control of the latter is possible through switch 4 through wire 37.

Manifestly, the construction set forth in the foregoing and shown in the accompanying drawing is capable of considerable modification and such modification as is considered 10 within the scope of the appended claims is also considered within the spirit of the invention.

I claim—

1. A fan including a motor, a bracket having opposite arms embracing opposite sides of the motor, means to pivotally connect the end portions of the arms to said opposite sides of the motor, a support overlying the bracket, means to turnably connect the bracket to the support, electrical connections between the support and the bracket for supplying current to the motor, oppositely disposed wings extending outwardly from and secured to opposite sides of the motor, and a propeller carried by the motor and arranged in the front of the wings.

2. A fan including a motor, a bracket having opposite arms embracing opposite sides of the motor, means to pivotally connect the 30 end portions of the arms to said opposite sides of the motor, a support overlying the bracket, means to turnably connect the bracket to the support, electrical connections between the support and the bracket for supplying current to the motor, oppositely disposed wings extending outwardly from and secured to opposite sides of the motor, a propeller carried by the motor and arranged in the front of the wings, braking means having rigid connection with the support, means carried by the bracket to engage the braking means, and means to operate the last named means at a point remote therefrom.

3. A fan including a motor, oppositely disposed wings extending outwardly from opposite sides of the motor, means to secure the wings to said sides of the motor, an overhead support, means to turnably support the motor from said overhead support, electrical connections between the overhead support and said motor support for supplying current to the motor, and a propeller carried by the motor and arranged in front of the wings.

4. A fan including a motor, oppositely disposed wings extending outwardly from opposite sides of the motor, means to secure the wings to said sides of the motor, an overhead support, means to turnably support the motor from said overhead support, electrical connections between the overhead support and said motor support for supplying current to the motor, braking means carried by the overhead support, means on said motor supporting means to engage the braking means, and

means to operate said means which engages the braking means thereby to brake the motor supporting means.

In testimony whereof I affix my signature.
